WINDING MACHINE

Harold Wood Hitchcock, Apponaug, R. I., assignor
to Universal Winding Company, Boston, Mass.,
a corporation of Massachusetts

Application April 27, 1939, Serial No. 270,455

16 Claims. (Cl. 242—43)

This invention relates to winding machines and particularly to improvements in machines for winding packages, cops, cheeses, bobbins and the like of different forms or shapes, for example, packages of either cylindrical or frusto-conical shape and in some cases shaped generally cylindrically or conically with tapered ends.

In the following specification and claims the term "package" is used in a general sense to apply to any form of wound mass of strand material and the term "yarn" is employed to indicate material either of a textile nature or otherwise.

One object of the present invention is to provide means in the winding machine for maintaining the reciprocating thread-guide in close relation to the surface on which the winding is performed while preventing it from making contact therewith as it traverses to-and-fro longitudinally thereof.

Another object of the invention is to provide an adjustable bail adapted to bear against the surface of the package and arranged to form a track or guideway for the reciprocating thread-guide to maintain the latter in close relation to the package surface without contact therewith.

Another object of the invention is to provide an automatically-adjustable thread-bail adapted to bear against the surface on which the winding is performed and self-adjusting to conform to said surface whether the latter be parallel with or at varying angles with respect to the axis of the package.

Another object of the invention is to provide a winding mechanism with a reciprocating thread-guide having an oscillating motion in addition to its reciprocation and provided with an elongate thread-slot in which the yarn plays back and forth to distribute the wear on the guide.

Another object of the invention is to provide a winding machine having the features hereinbefore mentioned and adapted for winding relatively soft packages of various forms or shapes with greater precision and having improved stability over those previously produced on machines of the present type.

Further objects of the improvement are set forth in the following specification which describes a preferred form of construction of the invention, by way of example, as illustrated by the accompanying drawings. In the drawings:

Fig. 1 is an end elevational view of a winding machine of conventional type embodying the improvements of the present invention;

Fig. 2 is a partial side elevation of the same

showing the winding spindle, traverse-frame, reciprocable thread-guide and other essential elements of the machine;

Fig. 3 is a fragmentary view of the winding spindle and traverse-frame viewed in the direction opposite to that of Fig. 2;

Fig. 4 is a plan view showing the winding spindle carrying a frusto-conical winding mandrel and illustrating the arrangement of the adjustable thread-bail pivotally mounted on the traverse-frame; and

Fig. 5 is a similar plan view showing a cylindrical form of winding mandrel with the thread-bail adjusted to cooperate therewith.

Referring particularly to Figs. 1 and 2, the winding machine herein illustrated is generally of well-known construction as comprising a main frame 2, a rotary winding spindle 3 journaled in bearings at the top of the frame, and a cam-shaft 4 arranged parallel with the spindle and journaled in bearings on the lower part of the frame. A swinging traverse-frame 5 of conventional form having a main horizontal portion 6 with depending legs, one of which is shown and designated 7, is pivoted on the cam-shaft 4. The traverse-frame 5 supports the reciprocable thread-guide 10, to be later described, to adapt the latter to move outwardly away from the winding spindle 3 during the growth in diameter of the package. The traverse-frame 5 is balanced by a counterweight 11 depending below its pivotal axis and its swinging movement is controlled by a dog 12 of usual construction arranged with its upper portion sliding in a tapered groove 35 in an arcuate quadrant 14 attached to the main frame 2 by a stud 15. A finger-lever 13, shown fragmentarily in Fig. 4, provides means for releasing the dog 12 from the quadrant 14 to permit manual adjustment of the traverse-frame 5 toward the winding spindle 3 at the start of a winding operation.

The quadrant 14 is pivoted on the stud 15 and provided with an upstanding portion 16 formed with a detent-shoulder 17 adapted to interengage with a lug or abutment 18 on the curved arm 19 of a starting lever 20. The starting lever 20 is mounted fast on a rockable rod 21, see Fig. 2, which is connected to the starting and stopping mechanism of the machine, for example, with means for engaging and disengaging a clutch which connects the power drive with the winding spindle 3 and cam-shaft 4 of the machine; these parts not herein shown and described in detail as they may be of any usual form as well known to those versed in the present art.

The starting lever 20 also carries a rearwardly-extending arm 22 mounting a brake-shoe 23 adapted to engage with the tapered periphery of a brake-disk 24 fast on the spindle 3, see Fig. 2. Suffice it to state herein that by rocking the starting lever or handle 20 in a clockwise direction as viewed in Fig. 1 the clutch is engaged to apply power to rotate the spindle 3 which is suitably connected to drive the cam-shaft 4; and during this application of the drive the 10 detent-abutment 18 on the arm 19 of the lever 20 is engaged with the detent-shoulder 17 on the quadrant 14 to maintain the machine operative. To arrest the operation of the machine the quadrant 14 is rocked upwardly on its pivot 15 15 to release the detents whereby a spring or other means, not shown, will throw the lever 20 to declutch the drive. The quadrant 14 may be rocked automatically when the yarn breaks or its supply is exhausted by means of a drop-wire or stopping lever 26 pivoted to the end of the quadrant at 27 with its end adapted to engage the teeth on a rotating wheel or disk 28 when the lever is released from the yarn. The quadrant 14 may be rocked automatically upon completion of the package by the engagement of a shoulder 29 on the traverse-frame 5 with the beveled face 30 of a block or stop-member 31 which is adjustable along the quadrant to determine the size of the package.

The horizontal portion 6 of the traverse-frame 5 is provided with a grooved guideway 32 which receives a reciprocable traverse-rod 35 carrying the thread-guide 10. The inner end of the traverse-rod 35 is attached to a crosshead 36 carrying a roller or bowl 37 which engages in a helical groove in a traverse-cam 40, shown fragmentarily in Fig. 2. The cam 40 is of usual construction having a cylindrical rim supported from a hub 41 mounted fast on the cam-shaft 4 to be rotated thereby.

The traverse-rod 35 is retained in the groove 32 of the traverse-frame 5 by an overlying portion of the traverse-frame back 43 which is made separate from and attached to the frame by screws 44 in accordance with the usual construction. The traverse-frame back 43 extends parallel with the axis of the winding spindle and at its upper end it is formed with a forwardly-projecting portion or lip 46 having a vertical face on its forward side with a sharply beveled edge extending rearwardly from the top thereof. It is noted here that in the standard form of construction of the present type of machine the traverse-frame back 43 is made removable from the main traverse-frame 5 in order that backs of different form may be substituted therefor in accordance with the shape of the package to be wound on the machine. That is to say, when parallel-sided or cylindrical packages are wound on the machine a traverse-frame back having a forward guiding face disposed parallel with the axis of the winding spindle is attached to the traverse-frame 5; whereas, when a package of frusto-conical shape is to be wound a substitute traverse-frame back with an inclined guiding face must be employed. A suitable tension-device is usually provided as an adjunct to the machine to apply tension to the strand of yarn feeding from its source of supply to the winding spindle 3. As so far described the winding machine is similar to those now generally used in the art.

The traverse-mechanism of the present machine as herein shown is adapted to wind pack-

ages of the shape indicated by dash lines in Fig. 2 of the drawings. Such packages P are formed with a generally conical body b and beveled or tapered ends e and f. In other cases the body of the package may be either tapered or straight with one end only beveled or it may take other similar shapes. To provide for winding this type of package the traverse of the reciprocating thread-guide 10 must be progressively shortened during the winding at one or both ends of the package and this may be effected by giving the guide an oscillating motion in addition to its reciprocatory movement. The means herein shown for oscillating the thread-guide at the ends of its traverse are similar to those illustrated and described in a co-pending patent application, Serial No. 734,824, filed by Hill and Seem July 12, 1934, now Patent No. 2,154,847 issued April 18, 1939.

In the present form of construction the thread-guide 10 consists of a relatively narrow blade having a hinge-like bearing 49 at its lower end pivoted on a pin 50 which is held in bearings 51 formed as a part of a sheet-metal member 52 carried by the traverse-rod 35. The member 52, in turn, is pivoted on a stud 53 riveted to an upright member or blade 55 secured fast at its lower end to the traverse-rod 35. The lower end of the blade 55 is received in a slot in the traverse-rod 35 and held in place by a set-screw 56. The blade 55 extends upwardly and is offset at the top with its upper end bearing against the forward face of the lip 46 on the traverse-frame back 43. A lug or extension 57 on the upper end of the blade 55 is bent across the edge of the lip 46 in engagement with its beveled face whereof to form a sliding connection between the blade and the traverse-frame back 43. It will thus be observed that the thread-guide 10 is arranged to rock on its pivot-pin 50 to move toward and away from the traverse-frame back 43; and likewise it is adapted to oscillate laterally with the member 52 pivoting on the stud 53 which connects said member to the blade 55. The rocking motion of the thread-guide 10 toward and away from the traverse-frame back 43 adapts the guide to follow the tapered contour of a conical package, the path of movement of the guide being controlled by a thread-bail 60 which forms one feature of the present invention.

The bail 60 is of bifurcated form, being conveniently constructed of wire rod having its ends bent at an angle to its main portion to form legs 62 and 63. As shown in Figs. 4 and 5, the ends of the legs 62 and 63 are inserted in holes in the upstanding ends of a rockable U-shaped cross-arm or bar 65 which is pivotally mounted on the upper part of the traverse-frame back 43. Suitable set-screws 66 at the ends of the bar 65 engage against the ends of the legs 62 and 63 of the bail 60 to secure the latter in adjusted relation to the bar, thus making it possible to change the position of the bail with respect to the bar in accordance with the shape of the package being wound. The rockable bar or cross-arm 65 is formed at its center with a bore 67 through which is riveted the upper reduced end of a pivot-pin or stud 68. The stud 68 has enlarged bearing bosses 69 journaled in a pair of spaced bearings 70 and 71 projecting from the rearward face of the traverse-frame back 43. To prevent too free turning movement of the bar 65 a relatively flat leaf-spring 73 is secured to the traverse-frame back 43 by a screw 74 with its

free end extending between the bearings 70 and 71 and engaging frictionally against the central reduced portion of the stud 68. Fastened to the rearward face of the traverse-frame back 43 is a "thread-guiding member 75 formed of sheet-metal with legs 76 at either end clamped to the traverse-frame back by screws 77. The upper portion of the member 75 is rolled over in an extended loop 78 forming a pathway for the strand of yarn *y* drawing thereacross as it feeds to the thread-guide 10. The thread-guide 10 is formed with an elongate slot 80 through which the strand *y* feeds from across the top of the thread-guiding member 75, the slot 80 having a flaring re-entrant opening to facilitate the threading of the yarn thereinto.

It will be noted by reference to Fig. 1 of the drawings that the thread-guide 10 normally bears against the straight portion of the thread-bail 60 which, as before stated, directs the course of its reciprocation and at the same time restrains it from contacting with the surface of the package on which the winding is being performed. In order to maintain the guide 10 in this relation to the thread-bail 60 while adapting it to travel therealong, a helical spring 81, shown most clearly in Figs. 1 and 4, tends to urge the guide outwardly away from the traverse-frame back 43. The spring 81 is coiled about a pin 82 projecting from an arm 83 formed as part of the member 52, the end of the pin also engaging through a slot 84 at the end of an arm 85 projecting laterally from the thread-guide 10, see Fig. 3. The spring 81 is tensioned between the arm 85 and a flange 86 on the pin 82. The pin 82 is secured fast in the arm 83 of the member 52 and projects therethrough to form a bearing or pintle for a roller 90, see Fig. 1.

The roller 90 is arranged to travel in the slot 91 of a guideway or track 92 which is pivoted to the forward face of the traverse-frame back 43 by a screw 93 as shown in Fig. 3. The track 92 acts through the roller 90 to control the position of the thread-guide 10 during the latter's reciprocation, whereby the extent of its traverse may be varied by changing the position of the track to oscillate the guide. In accordance with the invention shown and described in the Hill and Seem application, referred to above, the track 92 is caused to be oscillated on its pivot-screw 93 by the outward movement of the traverse-frame 5 during the building of the package. For this purpose the track 92 has its inner end formed with a projection or follower 94 which engages in an inclined cam-slot 95 in a member or plate 96 held on the stud 15 and secured fast to the main frame 2 of the machine by a bolt 97. The bolt 97 projects through a slot 98 in the downwardly extending arm 99 of the cam-plate 96 and by releasing the bolt the cam-plate may be adjusted to vary the relationship of its cam-slot 95. It will be understood that as the traverse-frame 5 swings outwardly with the thread-guide 10 receding from the winding spindle 3 as the package increases in diameter the projection 94 will slide down the incline of the cam-slot 95, thereby tilting the track 92 to raise its outer end above the horizontal. This tilting of the track 92 causes the thread-guide 10 to be gradually rocked inwardly away from the ends of its traverse as the roller 90 slides in the slot or guideway 91 of the track. In this way the extent of traverse of the thread-guide 10 is gradually lessened by the oscillating movement of the guide with relation to the traverse-rod 35

so that the package is built up with layers of gradually decreasing length to form the tapered ends of the package.

The essential elements of the winding machine having been described in detail its method of operation is explained as follows: A suitable paper tube or other yarn-carrier T is placed upon the mandrel carried by the winding spindle 3 and the strand of yarn *y* led up from its source of supply, 10 not herein shown, through the tension-device and passed over the thread-guiding member 75. From the curved surface of the member 75 the yarn is drawn forward through the slot 80 in the thread-guide 10, thence down across the thread-bail 60 and its end attached to the tube or yarn-carrier T. Figs. 1 to 4 of the drawings illustrate the yarn-carrier T on which the winding is to be performed as of conical shape to receive a similarly-shaped package and in the arrangement 15 of the machine as shown the package is built up with tapered ends. For this type of winding the thread-bail 60 is initially adjusted on the cross-arm 65 to align its straight portion with the surface of the tube or carrier T, the outer end of the bail being spaced at a greater distance from the end of the cross-arm than its inner end. This adjustment is necessary only for winding sharply 20 tapered packages as ordinarily the rocking motion of the cross-arm or bar 65 will adapt the 25 ball 60 to a slightly inclined surface, but as the 30 rocking of the cross-arm is limited somewhat by its outer ends striking against the traverse-frame 35 back 43 it has been considered preferable to provide for the adjustment noted.

After the bail 60 has been properly adjusted with respect to the cross-arm 65 the traverse-frame 5 is moved into position to cause the bail to bear against the surface of the yarn-carrier T, this being accomplished by releasing the dog 12 40 by means of the finger-lever 13 shown fragmentarily in Fig. 2. With the traverse-frame 5 adjusted to initial position in this manner the thread-guide 10 will be held away from the surface of the yarn-carrier T by the thread-bail 60 45 against which the upper end of the guide bears under the action of the spring 81.

The machine is started to operate by rocking the starting lever 20 to the right as viewed in Fig. 1, thereby engaging the detent-abutment 18 50 on its arm 19 with the detent-shoulder 17 on the extension 16 of the quadrant 14. During this movement of the starting lever 20 the brake 23 is released from the brake-disk 24 and the clutch or other drive-connecting means is actuated to 55 apply power to the winding spindle 3 and cam-shaft 4. As the spindle 3 is rotated in clockwise direction as viewed in Fig. 1 the yarn *y* is wound onto the tube or carrier T and traversed longitudinally thereof by the reciprocating movement 60 of the thread-guide 10 which is connected through the traverse-rod 35 to the helical cam 40. During its reciprocation the thread-guide 10 slides along the thread-bail 60 and due to the inclination of the bail with respect to the 65 axis of the winding spindle the guide is caused to rock back and forth about its pivot 50, being maintained constantly bearing against the bail by the spring 81. The bail 60 thus causes the guide 10 to follow the inclined surface of the winding without contact therewith, thus avoiding any abrading action of the guide on the yarn tending to roughen and damage the latter. As the helical coils of winding build up layers on the carrier T the bail 60, bearing against the surface of the winding, forces the upper portion of

the traverse-frame 5 outwardly away from the axis of the winding spindle 3. At the same time the counter-weight 11 causes the traverse-frame 5 to maintain the thread-ball 60 constantly bearing against the surface of the yarn wound onto the carrier T. Since the pressure of the package on the ball 60 which forces the thread-guide 10 and its support or traverse-frame 5 outwardly is distributed across the full length of the package there is less tendency to crush the yarn mass and consequently softer packages may be produced. Soft-wound packages are desirable for various purposes such as for dyeing or otherwise treating the yarn with fluids where a porous mass is of advantage; and also to prevent the crushing or matting of yarns of a soft or "lofty" nature.

At the start of the winding operation the cam-track 92 assumes a position with its slot 91 substantially parallel with the traverse-rod 35 so that as the thread-guide 10 is reciprocated with the traverse-rod the roller 90 on its arm 85 will have no effect to oscillate the guide. As the traverse-frame 5 recedes from the axis of the winding spindle during the increase in diameter of the winding the projection or follower 94 at the end of the cam-track 92 slides down the incline of the cam-slot 95, thereby causing the track to be rocked on its pivot-screw 93 to incline its outer end upwardly. Consequently, each time the traverse-bar 35 is reciprocated in either direction the thread-guide 10 will be rocked inwardly away from the end of its traverse, its pivotal connection at 53 with the blade 55 providing for this oscillating motion. In this manner as the inclination of the track 92 is increased the oscillating motion of the thread-guide 10 is augmented so that the length of traverse of the guide is gradually and progressively shortened. This results in gradually shortening the length of the layers of yarn deposited on the carrier T so that the package is built up with tapering ends as indicated by the dash lines in Figs. 2 and 3. The winding operation continues until the package reaches its predetermined diameter, whereupon the operation of the machine is arrested automatically by the engagement of the shoulder 29 on the traverse-frame 5 with the beveled face 30 of the sizing block 31. This engagement rocks the quadrant 14 upwardly to release its detent shoulder 17 from the abutment 18 on the starting lever 20, whereupon the latter is actuated by the spring, not herein shown, to declutch the drive.

When it is desired to wind cylindrical or parallel-sided packages on the machine the thread-ball 60 may be adjusted in substantially parallel relation to the rockable cross-arm or bar 65 as shown in Fig. 5. With this adjustment of the thread-ball the winding proceeds in the manner explained previously with the thread-guide 10 sliding along the straight portion of the ball 60 to restrain it from contacting with the surface of the winding, the ball acting as explained above to force the traverse-frame 5 outwardly away from the axis of the winding spindle as the package increases in diameter. In either case the pivotal mounting of the cross-arm or bar 65 provides for a rocking motion thereof so that the thread-ball may accommodate itself more precisely to the surface of the package. In other words, if the periphery of the package changes in shape, as is sometimes desired to form cones with an increasing taper, the cross-arm 65 will rock to adjust the ball to this change in angle.

larity of the surface on which the winding is being performed. The thread-ball 60 will thus be maintained bearing against the surface of the package being wound throughout the whole extent of the latter so that the pressure against the winding will be distributed over a relatively greater length of contact than where previously the guide has been arranged to bear against the package and to force the traverse-frame outwardly away from the axis of the winding spindle. The present arrangement of the thread-ball is therefore of advantage in winding soft packages and constitutes an improvement in the art as preventing undue pressure of the guide on the package tending to cause its collapse and also as eliminating frictional rubbing action of the guide on the yarn which with fine materials would have a deleterious effect.

It has also been determined in practice that the arrangement of the ball to adapt it to bear against the surface of the package being wound with the thread-guide spaced at a slight distance from this surface has another advantageous result as tending to produce more perfectly-shaped packages having greater stability at their ends. As the thread-guide 10 approaches the end of its traverse it has a tendency to whip or flutter due to play in the parts arising from clearances or as caused by wear. This fluttering action of the guide resulting from momentum and inertia of the parts causes the yarn to be whipped outwardly so that it may overrun the end of the package to cause loose loops termed "stitches" or "cobwebs" on the ends of the package. With the present form of construction and method of operation of the thread-guide the short length of yarn between the guide and the face of the package, that is the length extending across the ball 60, absorbs the false motion of the guide, thereby preventing the yarn from whipping out across the end of the package to cause irregularities and defects in the winding.

As another feature of improvement in the present invention it will be noted that since the thread-guide 10 oscillates back and forth during its reciprocation from one end of the package to the other the yarn y will ride up and down in its elongate slot 80 as the strand is maintained at a constant height by the thread-ball 60. Due to this sliding action of the yarn in the slot 80 of the thread-guide 10 the wear is distributed along the sides of the slot and consequently is prevented from cutting grooves in the guide as sometimes occur with hard materials such as silk and glazed yarns.

It will be observed from the foregoing that the present invention provides important improvements in the winding art which make for precise winding and result in a better product, the wound packages being of accurate shape and more stable in structure. While the invention is herein illustrated and described as embodied in a preferred form of construction, it is to be understood that various modifications may be made in the structure and arrangement of the parts of the machine without departing from the spirit or scope of the invention. Therefore, without limiting myself in this respect, I claim:

1. In a winding machine, means for rotating a package, a thread-guide for traversing yarn longitudinally of the package, means for actuating the thread-guide, a member interposed between the thread-guide and package to prevent contact of the guide therewith, and means where-
70 by said member may be initially adjusted to

adapt it to extend at various angles with respect to the axis of the package.

2. In a winding machine, means for rotating a package, a thread-guide for traversing yarn longitudinally of the package, means for actuating the thread-guide, and a relatively light wire ball pivotally mounted to adapt it to lie parallel with or extend in angular relation to the axis of the package, said ball providing a track for the thread-guide closely adjacent the package while preventing actual contact of the guide therewith.

3. In a winding machine, a winding spindle, a traversing thread-guide, said spindle and thread-guide being adapted to recede one from the other during the growth of the package wound on the spindle, and a member interposed between the thread-guide and winding spindle and adjustable at varying angles with respect to the axis of the latter to provide a track for the thread-guide to direct the course of the latter as it is traversed longitudinally of the winding spindle.

4. A winding machine having a rotary winding spindle and a traversing thread-guide adapted to recede one from the other during the increase in diameter of the package wound on the spindle, a ball interposed between the thread-guide and the winding spindle to provide a track for the thread-guide to maintain it free from contact with the package during its traverse longitudinally of the spindle, and means for mounting said ball to adapt it to adjust itself in angular relation to the axis of the winding spindle.

5. A winding machine comprising a rotary winding spindle and a reciprocating thread-guide adapted to separate during the increase in diameter of the package wound on the spindle, means for mounting said thread-guide to adapt it to rock toward and away from the axis of the winding spindle, a ball interposed between the thread-guide and the winding spindle to adapt it to bear against the surface of the package being wound to prevent the guide from contacting therewith, means for mounting the ball to adapt it to be adjusted in angular relation to the axis of the winding spindle, and means for maintaining the thread-guide bearing against the ball during its reciprocation longitudinally thereof.

6. A winding machine comprising a rotary winding spindle, a thread-guide reciprocable longitudinally of said spindle, a support for the thread-guide arranged to permit separation between said guide and spindle during the increase in diameter of the package being wound, a ball interposed between the thread-guide and winding spindle to adapt it to bear against the surface of the package, and means for mounting said ball on the thread-guide support to adapt the ball to adjust itself in angular relation to the axis of the winding spindle to conform to the surface of the package being wound, said ball being so constructed and arranged as to serve as a track for the thread-guide to direct the course of the latter during its traverse longitudinally of the spindle.

7. In a winding machine, a rotary winding spindle, a reciprocable thread-guide, means to support said thread-guide to adapt it to recede from the winding spindle during the growth of the package being wound, a ball interposed between the thread-guide and winding spindle to adapt it to bear against the surface of the package being wound on the spindle, means for mounting said ball to adapt it to be adjusted in angular relation to the axis of the winding spindle, and

means for maintaining the thread-guide bearing against the rearward side of the thread-ball as it is traversed longitudinally thereof whereby to adapt it to follow the surface of the package without contact therewith.

8. In a winding machine, a rotary winding spindle, a reciprocable thread-guide, a traverse-frame for supporting the thread-guide to adapt it to recede from the spindle during the growth of the package wound on the spindle, and a ball adjustably mounted on the traverse-frame to adapt it to conform to the surface of the package being wound and arranged between the thread-guide and the winding spindle, said ball engaging the guide to direct its course of reciprocation parallel to the surface of the package while preventing it from contacting therewith.

9. In a winding machine, means for rotating a package, a thread-guide for traversing yarn longitudinally of the package, means for actuating the guide, a movable frame for supporting the guide to adapt it to recede from the axis of the package during the growth in the winding, a member pivotally mounted on said frame, and a relatively light wire ball carried by said member to adapt it to adjust itself into position to align with the surface of packages of varying shape, said ball being interposed between the thread-guide and surface of the package and forming a track for the guide to prevent contact of the guide with the package.

10. In a winding machine, the combination of means for rotating a package, a thread-guide for traversing yarn longitudinally of the package, means for actuating the thread-guide, a traverse-frame for supporting the thread-guide to adapt it to move away from the axis of the package during the growth in the winding, and a ball pivotally mounted on the traverse-frame to adapt it to rock on an axis crossing the axis of the package, said ball being interposed between the thread-guide and the surface of the package and serving as a track against which the thread-guide bears to prevent the guide from contacting with the package.

11. In a winding machine, the combination of means for rotating a package, a thread-guide for traversing yarn longitudinally of the package, means for actuating said thread-guide, a pivoted member rockable about an axis crossing the axis of the package, and a ball mounted on said member to adapt it to bear against the surface of the package to prevent the guide from contacting therewith, and connecting means permitting adjustment of said ball in angular relation to the member to adapt it to conform to the surface of packages of different shapes.

12. In a winding machine, means for rotating a package, a thread-guide for traversing yarn longitudinally of the package, means for actuating said thread-guide, a movable traverse-frame for mounting the thread-guide to adapt it to recede from the axis of the package during the winding, a member pivoted to said traverse-frame to rock on an axis crossing the axis of the package, and a U-shaped ball having its legs mounted on said member and adapted to bear against the surface of the package to prevent contact of the guide therewith, said ball being so mounted on said member as to adapt its legs to be adjusted to vary its angularity with respect to the member.

13. In a winding machine, means for rotating a package, a thread-guide for traversing yarn longitudinally of the package, means for actuating the thread-guide, a ball extending longitudinally of the package and interposed between the sur-

face thereof and the thread-guide, means for pivotally mounting said bail to adapt it for automatic adjustment in alignment with the surface of the package, and resilient means for resisting the pivotal movement of the ball.

14. In a winding machine, means for rotating a package, a thread-guide for traversing yarn longitudinally of the package, means for actuating the thread-guide, a bail interposed between the thread-guide and the surface of the package, means for pivotally mounting the ball to adapt it for adjustment parallel with the surface of the package, and resilient means cooperating with the mounting to resist the pivotal movement of the ball.

15. A winding machine having a rotating winding spindle and a traversing thread-guide adapted to recede one from the other during the increase in diameter of the package wound on the spindle, a ball interposed between the thread-guide and the winding spindle to provide a track for the thread-guide to maintain it free from contact with the package during its traverse longitudinally thereof, a pivot for mounting said bail to adapt it to rock on an axis extending across the axis of the winding spindle, and a spring acting against said pivot to resist the rocking movement of the bail in adjusting itself in parallel relation to the surface of the package being wound.

16. A winding machine comprising a rotary winding spindle, a thread-guide reciprocable longitudinally of said spindle, means to reciprocate said guide, a support for the thread-guide arranged to permit separation between said guide and spindle during the increase in diameter of the package being wound, a bail interposed between the thread-guide and winding spindle to adapt it to bear against the surface of the package, a pivot for mounting said bail on the thread-guide support to adapt the bail to adjust itself in angular relation to the axis of the winding spindle, and a spring on the support acting against the pivot for the thread-ball to control the swinging movement of the latter.

HAROLD WOOD HITCHCOCK.
